CLAIM

The ornamental design for a faucet connector, as shown and described.

DESCRIPTION

FIG. 1 is a perspective view of a faucet connector showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is another perspective view of the faucet connector, shown with environment.

The broken lines in FIG. 8 showing two sleeves depict environment and form no part of the claimed design. The other broken lines in the drawings depict portions of faucet connector and form no part of the claimed design.

1 Claim, 8 Drawing Sheets
